UNITED STATES PATENT OFFICE.

GEORGE S. ADAMS, OF NEW YORK, N. Y.

DESIGN FOR A KITCHEN SPICE-CASTER.

Specification forming part of Design No. 5,980, dated July 16, 1872.

Specification describing a new and original Design for a Kitchen Spice-Caster, invented by GEORGE S. ADAMS, of the city, county, and State of New York.

The nature of my design is fully represented in the accompanying drawing, to which reference is made.

A is the caster, which consists of the body part A' and the cover B. C represents the caster-bottles, which contain the spices.

The drawing, Figure 1, represents the center open, and Fig. 2 a cross-section on the line x x.

The object is to provide a package for the

sale of spices, which, when opened, will expose the bottles containing the variety of spices used in cooking, so that they are ready and convenient for use.

Having thus described my invention, I claim as new and desire to secure by Letters Patent—

A design for a kitchen-caster, A, substantially as and for the purposes described.

GEORGE S. ADAMS.

Witnesses:

C. SEDGWICK,
ALEX. F. ROBERTS.
